No. 811,151.

PATENTED JAN. 30, 1906.

G. M. KNEUPER.

FILTER.

APPLICATION FILED MAY 17, 1906.

UNITED STATES PATENT OFFICE.

GEORGE M. KNEUPER, OF NEW YORK, N. Y.

FILTER.

No. 811,151.

Specification of Letters Patent.

Patented Jan. 30, 1906.

Application filed May 17, 1905. Serial No. 260,832.

To all whom it may concern:

Be it known that I, GEORGE M. KNEUPER, a citizen of the United States, and a resident of the borough of Manhattan, city, county, 5 and State of New York, have invented certain new and useful Improvements in Filters, of which the following is a specification.

My invention relates to filters, and has for its object to provide a filter which shall be 10 inexpensive to manufacture, rapid in its action, and which can be easily taken apart for any purpose whatsoever.

My invention will be fully described hereinafter, and the features of novelty will be 15 pointed out in the appended claims.

Reference is to be had to the accompanying drawings, in which—

Figure 1 is a vertical section on line 1.1 of Fig. 2 of a filter made according to my invention, and Fig. 2 is a horizontal section on line 22 of Fig. 1.

A represents the outer shell of the filter, to which is secured at its lower end an outlet B, which is preferably funnel-shaped. A cap C is secured in any convenient manner to the upper end of the shell A, said cap C being provided with a neck C', having a central opening, the purpose of which will be more fully explained hereinafter.

D is a perforated mantle or cylinder preferably made of wire screening, and E is a cylinder of pulp of a kind suitable for filtering purposes. It is to be understood that the wire cylinder D and the pulp cylinder E are prepared in 35 a suitable way so that the pulp will extend into the meshes of the wire cylinder, thus securing the pulp cylinder and the wire cylinder together. These two cylinders D and E, forming practically a single cylinder, are secured 40 in place in the filter-shell A by the following means: A head or cap F, which fits over the upper ends of the cylinders and is provided with a central opening, abuts against the cap C with its central opening in registry with 45 the opening in the cap C. The lower ends of the cylinders D and E extend into a head or cap G, also provided with a central opening. Both of the caps F and G are beveled on the inside, as shown at F' and G', to more 50 surely hold the cylinders in place. It is also to be understood that the pulp cylinder E is somewhat longer than the wire cylinder D, so that when the caps are placed on the said cylinders the ends of the pulp cylinder E 55 will be turned inward, as shown at E'. A supply-pipe H, provided with apertures H'

and screw-threaded at both ends, extends through the caps C and F into the cylinders D and E and through the cap G. A nut I, having handles I', is screwed on the lower end 60 of the pipe H, which is closed by a plug H² and serves to secure the cap G in position, and a nut J, having handles J', is screwed upon the upper end of the pipe H against the neck C' of the cap C and serves to hold the two cylinders firmly in position in the filter. A nipple K is secured to or forms part of the nut J and is adapted to receive the end of a rubber tube or other connection communicating with the source from which the liquid to be 65 filtered flows.

As the liquid enters the filter through the apertures H' of the supply-pipe H the pulp cylinder becomes saturated therewith and expands, but owing to the fact that said 70 pulp cylinder is held by the wire cylinder expansion can only take place inwardly toward the source of supply, excepting at the ends, where the said cylinder expands to form an absolutely tight joint between it 75 and the two end caps F and G. This arrangement does away with the necessity of having rubber or other gaskets or washers at the ends to form tight joints. In filters of this kind the pulp has been held under great 80 pressure, and as the fluid to be filtered came in contact with the pulp the said pulp began to expand. As the said pulp, however, was prevented from fully expanding it became 85 dense and filtration could only be accomplished by great pressure. Moreover, what filtration does take place in filters of this kind is not fiber filtration at all, as the fluid is simply forced through the interstices formed by the indiscriminate crossing and crowding of 90 fibers. These defects are overcome in my device owing to the fact that the pulp cylinder is permitted to expand toward the center, thus forming a fiber filter in which the fibers of the pulp are free to act in the most 95 efficient manner as a filtering medium. Another advantage of my structure is the fact that filtration in this case is radial—that is, from a center of supply lateral and outward—so that the surface of intake is smaller than 100 the surface of discharge. This results in the minimizing of friction and also makes the filter very fast. My filter also possesses the important advantage of being self-adjustable—that is, it adjusts itself automatically 105 to any degree of pressure of the fluid.

My filters are not only useful for filtering

water, but can be used for honey, syrup, oils, and varnishes—in fact, anything that can be supplied to them either by gravity or pressure.

Various modifications may be made without departing from the spirit of my invention.

I claim—

1. A filter comprising two end members or heads, a perforated mantle extending from one head to the other, and a pulp lining on the inner surface of said mantle, the ends of the lining engaging the heads to form tight joints therewith, and the inner surface of the lining being exposed so that the inward expansion of the pulp lining is unrestricted.
2. A filter comprising two end members or heads, a perforated inlet-pipe connecting said head, a perforated mantle extending from one head to the other, a shell surrounding said mantle and having an outlet, and a pulp lining on the inner surface of said mantle, the ends of the lining engaging the heads to form tight joints therewith, and the inner surface of the lining being exposed so that the inward expansion of the pulp lining is unrestricted.
3. A filter comprising two end members or heads beveled on their inner surfaces, a perforated mantle extending from one head to the other end engaging said beveled surfaces,

and a filtering-lining on the inner surface of said mantle.

4. A filter comprising two end members or heads, a perforated mantle extending from one head to the other, and a filter-lining on the inner surface of the mantle and extending into the perforations thereof, the ends of the lining engaging the heads to form tight joints therewith, and the inner surface of the lining being exposed so that the inward expansion of the pulp lining is unrestricted.

5. A filter comprising two end members or heads, a perforated pipe connecting them, a perforated mantle surrounding the pipe and extending from one head to the other, a filter-lining on the inner surface of the mantle, a cap engaging one of said heads, means for pressing said cap toward the heads, and a shell connected with said cap and surrounding the mantle.

In testimony whereof I have hereunto set my hand in the presence of two subscribing witnesses.

GEORGE M. KNEUPER.
